UNITED STATES PATENT OFFICE.

PAUL B. RENFREW AND RAYMOND W. BOND, OF FORT WAYNE, INDIANA, ASSIGNEES
TO S. F. BOWSER & COMPANY, INC., OF FORT WAYNE, INDIANA, A CORPORATION
OF INDIANA.

DESIGN FOR A DISPENSING PUMP.

Application filed March 8, 1928. Serial No. 25,769. Term of patent 14 years.

To all whom it may concern:

Be it known that we, PAUL B. RENFREW and RAYMOND W. BOND, citizens of the United States and residents of Fort Wayne, in the county of Allen, and State of Indiana, have invented a new, original, and ornamental Design for a Dispensing Pump, of which the following is a specification, reference being had to the accompanying drawing, forming a part thereof.

In the drawing, the figure is a perspective view of a dispensing pump showing our new design.

We claim:

The ornamental design for a dispensing pump, as shown.

Fort Wayne, Indiana, February 28, 1928.

PAUL B. RENFREW.
RAYMOND W. BOND.
